(57) **CLAIM**

The ornamental design for a cleaning center for a shaver, as shown and described.

DESCRIPTION

FIG. 1 is a perspective view of cleaning center for a shaver; FIG. 2 is a front view thereof; FIG. 3 is a right side view thereof; FIG. 4 is a rear view thereof; FIG. 5 is a left side view thereof; FIG. 6 is a top plan view thereof; and, FIG. 7 is a bottom plan view thereof.

The broken lines illustrate portions of the cleaning center for a shaver and form no part of the claimed design.

1 Claim, 7 Drawing Sheets
